F. O. KILGORE,
CUSHIONING DEVICE FOR AUTOMOBILES AND LIKE VEHICLES.
APPLICATION FILED JAN. 10, 1910.

1,076,042.

Patented Oct. 21, 1913.

UNITED STATES PATENT OFFICE.

FREDERICK O. KILGORE, OF SOMERVILLE, MASSACHUSETTS.

CUSHIONING DEVICE FOR AUTOMOBILES AND LIKE VEHICLES.

1,076,042.

Specification of Letters Patent. Patented Oct. 21, 1913.

Application filed January 10, 1910. Serial No. 537,163.

To all whom it may concern:

Be it known that I, FREDERICK O. KILGORE, a citizen of the United States, residing in Somerville, county of Middlesex, and State of Massachusetts, have invented an Improvement in Cushioning Devices for Automobiles and like Vehicles, of which the following description, in connection with the accompanying drawings, is a specification, 10 like letters on the drawings representing like parts.

This invention relates to a cushioning device or apparatus especially adapted for use on automobiles and is an improvement upon 15 the cushioning devices shown and described in U. S. Patents No. 889,619 and No. 923,858 granted to me June 2, 1903 and June 8, 1909 respectively.

The present invention has for one of its 20 objects to simplify and improve the cushioning device, whereby the device can be easily and quickly adjusted to cars having different spring power or strength of springs which support the car body, which adjustment can be conveniently effected in a minimum time after the cushioning device has been applied to the automobile.

The invention further has for its object 25 to provide a cushioning device with which the car body spring may be left practically free to move downward under the load in the car, but which is resisted in its upward or recoil movement, thereby avoiding throwing the occupants of the car up off of the 30 seats on the upward movement of the car body springs.

These and other features of this invention will be pointed out in the claims at the 35 end of this specification.

40 Figure 1 represents a sufficient portion of an automobile provided with a cushioning device embodying this invention to enable it to be understood. Fig. 2, a longitudinal section on an enlarged scale of the cushioning device shown in Fig. 1. Fig. 3, a similar section on a smaller scale of the device in its closed or contracted position, and Figs. 4 and 5, details in section on an enlarged scale to be referred to.

45 The cushioning device forming the subject of this invention is in the main the same as shown and described in the patents referred to, except as to features, which will be hereinafter pointed out.

50 Referring to the drawings, *a* represents a

cylindrical member, which is closed at its ends by the fixed head *b* and removable head *c*, and contains the reciprocating piston *d*, having its rod *e* extended through the head *c* and packing ring *f*, and secured at its end to the head *g* of a cylinder *h*, which is open at its lower end so as to fit over and slide upon the cylinder *a*. The cylinder *a* is designed to be secured to the car-body-supporting spring *i*, or it may be an axle of the car and may be designated the stationary member of the device, and the cylinder *h* is designed to be secured to the car body *j* so as to move therewith, and may be designated the movable member of the device. The cylinder *h* may and preferably will contain within it a dust guard or hood *k*, surrounding the piston rod and secured at its upper end to the piston rod *e* and at its lower end to the head *c*. The cylinder *a* may be provided with antifriction rings or blocks *l*, which contact with the inner side of the cylinder *h*.

The cylinder *a* is made of substantial thickness and sufficient to enable a cylindrical passage *m* to be drilled or otherwise formed in it, which extends from the lower end of the cylinder to near the upper end thereof and which communicates with the interior of the cylinder through ports *n*, *o*, *p*, located at suitable distances from the ends of the cylinder to be closed by the piston *d* and thereby form in the cylinder closed air spaces or chambers at the opposite ends of the same.

The passage *m* may be designated a valve chamber in which is located a valve *q*, shown as a rod provided at its outer end with a handle *r* and above said handle with screw-threads *s*, which engage corresponding screw-threads *t* on the inner circumference of the valve chamber *m*. The valve *q* is made long enough to co-operate with the port *n*, so as to control the passage of air from one side of the piston to the other. In the present instance, the valve *q* extends beyond the port *n*, and is provided with a substantially large hole or chamber *u* having in its walls a port *v*, which is adapted to register with the port *n*, so as to connect the chamber *u* with the cylinder *a*.

It will be seen that by partially rotating or turning the valve rod *q*, the port *n* in the wall of the cylinder *a* may be closed or

opened or partially closed, so as to regulate the flow of air from the upper part of the cylinder into the lower part of the cylinder, and vice versa, and thereby adjust the air cushion to the strength of the car body springs 10. The chamber 30 in the end of the valve rod constitutes in itself a valve chamber, with which co-operates a valve 40 on a rod 41, having its lower end extended into an opening or hole 42, extended from the bottom of the valve chamber 30 and constituting a guideway for the said rod in its movement. The rod 41 is made of sufficient length to engage the end wall 44 of the chamber 20, when the said rod has been moved to open wide the valve 40, and the hole 42 is made of sufficient length to prevent the rod 41 from being withdrawn therefrom before it engages the end wall 44. The valve 40 is preferably made smaller than the width of the chamber 30, so that the mouth of the chamber will not be entirely closed when the valve is in its lowermost position with its rod resting on the bottom wall of the hole 42, as represented in Figs. 2 and 4, thereby allowing a restricted opening for the passage of air from the chamber 20 into the cylinder *a* through the chambers 30 and ports 31, 21.

By reference to the drawings, it will be seen, that, when the piston *d* is descending in its cylinder as indicated by the arrow 50, Fig. 2, the air in the cylinder below the piston is forced out through the ports 21, 31, into the chamber 30, from which it passes into the chamber 20 and through the port 22 into the cylinder *a* above the piston. The air forced out of the chamber 30 carries with it the valve 40 and opens the same wide as represented in Figs. 3 and 5, that is, until it uncovers the mouth of the chamber 30 and affords a free passage for the air from the lower to the upper side of the piston. This arrangement enables the car body spring to freely respond downward to the motion of the car. On the other hand, when the car body spring recoils or moves upward, the air is forced from the upper part of the cylinder, through the port 22 into the chamber 20, thence down in the latter, carrying with it the valve 40, which is moved into the mouth of the chamber 30 so as to partially close the same, and thereby diminish the quantity of air which can be forced from the upper to the lower end of the cylinder in a given time, consequently retarding the upward movement of the piston *d* and of the car body springs. In this manner, a sudden recoil of the car body springs is avoided, and the disagreeable results of the same to the occupants of the car are likewise avoided, and a smoother and easier riding car is obtained.

The valve 40 may be properly designated the recoil valve and while I have shown one

arrangement of the same, which I may prefer, I do not desire to limit the invention in this respect.

While I may prefer to use the recoil valve in conjunction with the hand-operated valve 220, I do not desire to limit the invention in this respect, as either alone can be used to advantage.

The hand-operated valve can be manipulated after the cushioning device has been applied to the car, as it is only necessary to turn the handle 23 and uncover more or less of the port 21, in order to adjust the cushioning device to the strength of the car body springs. The packing ring *f* is securely held in the head *c* of the cylinder *a* by an externally threaded ring 60, which engages an internally threaded socket 61 in the said head and co-operates with a flange 62 on the packing ring to firmly fasten the packing ring to the cylinder head. The ring 60 is capable of being quickly and easily applied to or removed from its socket, and affords a convenient and reliable means for fastening and retaining the packing ring *f* in place.

I have herein described the invention as embodied in an apparatus employing air, but I do not desire to limit the invention in this respect, as the invention could be used with good results in an apparatus employing a liquid.

Claims.

1. In an apparatus of the class described, in combination, a cylinder provided with a passage extended longitudinally thereof and having ports separated from each other for connecting said passage with the interior of said cylinder, a valve rod extended into said passage and accessible from outside of said cylinder and provided at its upper end with a valve chamber having a port capable of registering with one of the ports in said cylinder, a valve rod extended into said valve chamber and provided with a valve co-operating with said valve chamber to afford a free passage for the air through the valve chamber in one direction and to restrict the passage of air through the valve chamber in the opposite direction, and a piston in said cylinder co-operating with the ports therein, substantially as described.

2. In an apparatus of the class described, in combination, a cylinder provided with a passage extended longitudinally thereof and having ports separated from each other for connecting said passage with the interior of said cylinder, a manually operated valve co-operating with one of said ports to regulate the passage of fluid within the cylinder through said passage, and an automatically operated valve located in said passage and arranged to be bodily moved away from said manually operated valve to permit a free flow of fluid through the passage in one di-

rection and to be bodily moved toward said manually operated valve to restrict the flow of fluid through said passage in the opposite direction, said automatic valve being guided 5 in its movement by said manually operated valve, substantially as described.

3. In an apparatus of the class described, in combination, a cylinder provided with a passage in its walls extended from one end 10 of the cylinder longitudinally toward the other and having ports separated from each other for connecting said passage with the interior of the cylinder, a manually operated valve extended into said passage from the 15 lower end of said cylinder, and a valve located in said passage above the manually operated valve and guided thereby to permit a free flow of the fluid through said passage into the cylinder in one direction and to re-

strict the flow of the fluid in the opposite 20 direction, and a piston in said cylinder, substantially as described.

4. In an apparatus of the class described, in combination, a cylinder provided with 25 ports near its opposite ends, a passage connecting said ports, a piston in said cylinder, a manually operated valve extended into said passage from one end of the cylinder, and an automatically operated valve located in said passage and guided by the manually 30 operated valve, substantially as described.

In testimony whereof, I have signed my name to this specification in the presence of two subscribing witnesses.

FREDERICK O. KILGORE.
